(57) **CLAIM**

I claim the ornamental design for the queen palm tree trimmer, as shown and as described.

DESCRIPTION

FIG. 1 is a perspective view of a person using the queen palm tree trimmer;

FIG. 2 is a perspective view of the queen palm tree trimmer;

FIG. 3 is a front view of the queen palm tree trimmer;

FIG. 4 is a back view of the queen palm tree trimmer;

FIG. 5 is a side view of the queen palm tree trimmer;

FIG. 6 is a other side view of the queen palm tree trimmer;

FIG. 7 is a top view of the queen palm tree trimmer; and,

FIG. 8 is a bottom view of the queen palm tree trimmer.

The broken line showing of the man and the palm tree are included for the purpose of illustrating environment and forms no part of the claimed design.

The drawings are shown broken away to indicate an indeterminate length. The broken lines of the handle are to show boundaries and form no part of the claimed design.
